UNITED STATES PATENT OFFICE

CHARLES S. PIDGEON, OF AKRON, OHIO

DOOR OPERATING MECHANISM

Application filed May 12, 1930. Serial No. 451,593.

This invention relates to door operating mechanism and more particularly to mechanism for operating garage doors.

The general object of the invention is to provide inexpensive, foolproof and efficient door operating apparatus.

It is also an object of the invention to provide means for connecting the operating mechanism with the doors so that the force of the operating mechanism will be applied to the doors in the most beneficial manner to move the doors.

A further object of the invention resides in the provision of improved means for limiting the opening and closing movement of the doors.

The above and other objects of the invention are achieved by the apparatus illustrated in the accompanying drawings and described below, it being understood that the invention is not limited to the specific details thereof shown and described.

In the drawings:

Figure 1 is an elevation of the garage doors looking from the inside of the garage;

Figure 2 is a plan view of the doors illustrated in Figure 1;

Figure 3 is a detailed view of Figure 1 taken on line 3-3 thereof;

Figure 4 is a plan view of the operating mechanism embodying the invention;

Figure 5 is a side elevation of the mechanism shown in Figure 4;

Figure 6 is a sectional view taken on line 6-6 of Figure 4; and

Figure 7 is a diagrammatic view of the control wiring of the operating means.

Referring to the drawings, the numerals 8 indicate a pair of doors, such as garage doors, which are hinged at their sides as at 9 to door frames or jambs 10. Secured to each of the doors 8 by brackets 13 and 14 are U-shaped, resilient metal members 15. The brackets 13 are formed with round holes to receive the member 15, but the brackets 14 receive the member in slots 16 as illustrated in Figure 3. The legs of the U-shaped member 15 are offset relatively to each other, as shown in Figure 2, so that the upper leg carried in the slot 16 of the bracket 14 is normally near the middle of the slot (Figure 3).

In order to connect the doors with the operating mechanism hereafter described, links 17 are provided which are connected to the ends

of the upper legs of the U-shaped member by pins 18.

To insure some means of allowing the doors to be opened in case the operating mechanism fails to function, the pin 18 on one of the doors is elongated and is eccentrically and pivotally connected to a disk 19 fixed to a shaft 20. The shaft 20 extends through the door and can be rotated from the outside of the garage by a handle 23 secured thereto. A lock is preferably provided on the handle 23 to prevent undesired entry to the garage in this manner. A spring clip 21 or other suitable supporting means is provided to support the link 17 during the opening of the door in this manner.

The operating mechanism comprising the invention is illustrated in Figures 4, 5 and 6 and includes a base channel 24 which is secured to the ceiling of the garage by any suitable means (not shown) which are best adapted to meet the requirements of the particular installation.

A reversible motor 25 fixed to one end of the upper side of the channel 24 drives a screw 26 journaled in bearings 27 and located at the bottom side of the channel. Suitable gearing, such as a pinion 28 secured to the motor shaft and a gear 29 fixed to the extending end of the screw 26, may serve to complete the drive between the motor 25 and the screw 26.

Carried by the screw 26 and in threaded engagement therewith is a cross-head 30, to the outer extending ends of which are pivotally attached, as at 33, the links 17 which are connected to the doors. The cross-head 30 is formed so that the side flanges and bottom of the channel 24 serve as guides for the cross-head, thus preventing accidental bending of the screw.

A three-armed lever 34, 35 and 36 having a central hub 37 is pivotally secured to the side of the channel 24 adjacent the motor 25 by a shouldered bolt 38. The arm 34 of the lever is pivotally connected with a rod 39 which extends slidably through a post 40 secured to the other end of the channel 24.

A collar 43 adjustably secured to the rod 39 is adapted to cooperate with a U-shaped fork 44 integral with one end of the cross-head 30 as the cross-head nears the outward end of its travel, to rock the three-armed lever. A spring 41 may be provided between the post 40 and collar 43.

In the inward movement of the cross-head 30, the three-armed lever is rocked by a screw

45 adjustably secured to the cross-head, which screw contacts with the arm 36 of the three-armed lever.

The arm 35 of the three-armed lever is 5 pivotally attached to one end of a dashpot 46 which comprises a cylinder 47 filled with a liquid 48 and having a piston 49 which makes a loose fit therein. The other end of the dashpot 46 is pivotally connected to one end of a metal strap 50 which is pivotally secured as 10 at 53 to a bracket 54 fixed to the channel.

Fixed to the middle of the strap 50 is a piece of brake lining 55 which cooperates with a drum 56 on the motor shaft when the 15 three-armed lever is rocked.

The downward movement of the dashpot is limited by a stop bracket 51 fixed to the channel 24, which stop engages with the strap 50.

20 A gutter 57 is preferably mounted on strap iron 60 below the channel to prevent drippings from the operating mechanism falling upon the car or other articles in the garage. The gutter may be hinged as at 58 and normally held up on the other side by a pin 59 received in aligned holes in the straps 60.

Figure 7 illustrates the control circuit for the motor 25. The motor, in the embodiment 30 of the invention described, is a reversible repulsion induction motor having starting leads S and running leads R. The motor is controlled by one or more switches 63 which are placed in parallel as shown when more 35 than one switch is used. The switches are of a standard type well known in the electrical art and comprise a hand knob which may be turned from O (off) to either F (forward) or R (reverse). The switch itself contains an overload coil which, if the motor is overloaded, causes the switch to kick out and causes the knob to return to O (off) position. The switches may be placed where desired, but one is usually mounted adjacent 40 the drive, in which position it can be operated without leaving the car. Another switch may be placed in the house or on the outside of the garage.

The operation of the mechanism is as follows:

When it is desired to open the doors, either 50 of the switches 63 are thrown to F (forward) which may be marked Open and the motor 25 is energized and rotates the screw 26 to move the cross-head 30 outwardly.

The links 17 connected from the cross-head to the upper legs of the U-shaped members 55 tend to swing the doors open. The slots 16 in the brackets 14 allow the upper legs of the U-shaped members 15 to move therein so that the actual force exerted by the links 17 on the door is transmitted to the bottom thereof by the spring or resiliency of the U-shaped members 15. While the drawings illustrate 60 the application of the force to the bottom of

the doors, the invention also contemplates applying it to the center of the doors rather than at the bottom, or at both. Applying the force at the bottom of the doors insures a smoother operation thereof as in a vertically hinged door binding most usually occurs at this point due to the sagging of the door. It may be that the doors are rather tightly stuck, under which circumstances the upper legs of the U-shaped members will move to the ends of the slots 16 so that further movement of the cross-head will tend to move the top of the doors as well as the bottom outwardly.

As the doors in their outward swing near their fully open position, the fork 44 integral with the cross-head 30 engages with the collar 43 to move the rod 39, thus swinging the three-armed lever to raise lever 35. As lever 35 is connected to braking straps 50 by the dashpot 46, the upward movement of the lever causes the brake lining 55 carried on the strap 50 to be forced against the drum 56. Further outward movement of the cross-head only increases the braking force between the drum 56 and the lining 55 so that the motor is overloaded and the switch 63 kicks to the off position to stop the motor and the outward opening movement of the doors. As the 80 brake is still applied to the motor shaft at the time the motor is cut off, there is no coast to the motor which is desirable in that the closing and opening limits of the door movement can be accurately adjusted.

To close the doors, either of the switches 63 may be thrown to R (reverse) which may be marked Close, thus reversing the motor to begin to move the cross-head 30 back or inwardly. The motor can be reversed as the 90 braking force applied through the dash pot 46 has receded or vanished as the liquid 48 in the dash pot has flowed by the loose fitting piston 49 shortly after the brake is first applied. This downward movement of the piston 49 in the cylinder 47 during the equalization of pressures on opposite sides of the piston is limited by the stop bracket 51. Thus as the cross-head 30 begins to move inwardly and carries the fork 44 away from the collar 43, the cylinder 47 will fall by its own weight 100 to move the three-armed lever and rod 39 to their original positions. The spring 41 will assist the cylinder 47 in this movement. It will be seen that in this operation the piston 49 does not move downwardly because the strap 50 rests on the stop 51, but that the cylinder 47 slides down on the piston, the liquid 48 moving past the loose fitting piston as will be understood.

The dashpot 46, the rod 39 and the three-armed lever are thus moved to their original position soon after the cross-head 30 begins its inward movement so that the cross-head approaches its limit of inward movement and the screw 45 carried thereby engages with 110

the arm 36 of the three-armed lever. Farther inward movement of the cross-head 30 applies the brake to the drum 56 through the agency of the dashpot 46 which overloads 5 and abruptly stops the motor as before by kicking off the switch 63.

In the closing movement of the doors, the U-shaped members 15 function as before to apply the force initially at the bottom of 10 the doors and then, if necessary, at the top as well.

By adjusting the screw 45 and the collar 43 the opening and closing limits of the door movement can be adjusted. The length of 15 the links 17 may, of course, be adjusted.

If for some reason, such as the failure of the electric current, the operating mechanism would fail to function, the doors may be opened by turning the handle 23 on the out- 20 side of the doors which will rotate the disk 19 and pull the pin 18 out so that it no longer connects the link 17 and the upper leg of the U-shaped members 15 which will allow the door to be opened by hand. The other connecting pin 18 can now be removed also so that the other door may be opened.

When it is necessary or desirable to oil the screw and its bearings, the pins 59 holding the gutter 57 up may be removed per- 30 mitting it to swing down so that grease cups or other lubricating means (not shown) in the bearings 27 and cross-head may be replenished.

While the invention has been particularly 35 described with respect to garage doors, it will be apparent that the principles thereof are applicable broadly to doors of all kinds. Moreover, even though the invention is primarily designed for the operation of a pair 40 of vertically and oppositely hinged swinging doors, by slight modifications it could be used to operate single doors which are either slide- able or are other than vertically hinged.

The mechanism is simple, it has few wear- 45 ing parts, which parts need lubricating but rarely, it is foolproof and efficient and the operating force is applied to the doors in the most effective manner.

Whereas many changes could be made in 50 the construction and application of the invention other than those described above, it is intended that all matter contained in the above description or shown in the accom- 55 panying drawings shall be interpreted as illustrative only and not in a limiting sense. Accordingly, various modifications of the invention can be resorted to without departing from the spirit thereof or the scope of the appended claims.

What is claimed is:

1. In mechanism for operating a vertically hinged door, the combination of operating means secured above the door, and connecting means between the door and the operating 65 means so constructed and arranged as to

apply the force of the operating means ini- 70 tially to the door at a point remote from the top thereof and upon failure of such initial force to move the door to apply an added force to the door at the top thereof.

2. In mechanism for operating a door, the combination of an operating member positioned adjacent one radially disposed edge of the door, and means connecting the door and the operating member, said connecting means being so constructed and arranged as to apply the force of the operating means ini- 75 tially to the door at a point remote from said radially disposed edge and upon failure of such initial force to move the door, said connecting means applying an added force to the door adjacent said radially disposed edge.

3. In mechanism for operating a door, the combination of operating means secured ad- 80 jacent one radially disposed edge of the door with means connecting the door and the operating means, said connecting means applying the force of the operating means initially 85 to the door at a point remote from said ra- dially disposed edge, and means in said connecting means for applying an additional force to the door adjacent said radially dis- 90 posed edge upon failure of the initially ap- plied force to move the door.

4. In mechanism for operating a door, the combination of operating means secured ad- 95 jacent one radially disposed edge of the door with means connecting the door and the operating means, said connecting means applying the force of the operating means initially to the door at a point remote from said radially disposed edge and upon failure of such initial force to move the door, said connecting means applying an added force to the door 100 adjacent said radially disposed edge, said connecting means including a U-shaped mem- 105 ber, the base of the U being connected par- allel with and adjacent the hinges of the door, one leg of the U being fixed to the door and the other leg having limited movement with respect thereto.

5. In combination, a vertically hinged door, a U-shaped member secured to said door, the base of the U being swivelly car- 110 ried parallel with and adjacent the hinges of said door, one leg of said U being secured to the door, the other leg of the U being offset with respect to said first named leg and car- 115 ried in a slot in a bracket fixed to said door, operating means mounted adjacent said door, 120 and means connecting the operating means with said last named leg.

6. In combination, a door, a U-shaped member secured to said door, the base of the U being swivelly carried parallel with and adjacent the hinges of said door, one leg of said U being secured to the door, the other leg of the U being carried in a slot in 125 a bracket fixed to said door, operating means 130

mounted adjacent said door, and means connecting the operating means with said last named leg.

7. In combination, a door, a U-shaped member secured to said door, the base of the U being swivelly carried parallel with and adjacent the hinges of said door, one leg of said U being secured to the door, the other leg of the U being carried in a slot in a bracket fixed to said door, operating means mounted adjacent said door, said operating means including a screw, an electric motor for reversibly rotating said screw, a cross-head carried by said screw, means for braking said motor at the ends of travel of the cross-head to overload and stop the motor, said braking means being operated by a dashpot, and means connecting said cross-head with the last named leg of the U-shaped member.
8. In combination, a door, a U-shaped member secured to said door, the base of the U being swivelly carried parallel with and adjacent the hinges of said door, one leg of said U being secured to the door, the other leg of the U being carried in a slot in a bracket fixed to said door, operating means mounted adjacent said door, said operating means including a screw, an electric motor for rotating said screw, switch means for controlling the direction of rotation of said motor, a cross-head carried by said screw, means for braking said motor at the ends of travel of the cross-head to overload and stop the motor, and means connecting said cross-head with the last named leg of the U-shaped member.

9. In combination, a door, a U-shaped member secured to said door, the base of the U-shaped member being hinged to said door, one leg of the U-shaped member being fixed to the door and the other leg having limited movement with respect thereto, a screw journaled adjacent said door, means for reversibly rotating said screw, a cross-head engaging with said screw, connecting means between said cross-head and said last named leg of the U-shaped member, and braking means for overloading and stopping said screw rotating means when the door has reached its fully open or closed positions.

10. In combination, a door, a U-shaped member secured to said door, the base of the U-shaped member being hinged to said door, one leg of the U-shaped member being fixed to the door and the other leg having limited movement with respect thereto, a screw journaled adjacent said door, means for reversibly rotating said screw, a cross-head engaging with said screw, connecting means between said cross-head and said last named leg of the U-shaped member, braking means for overloading and stopping said screw rotating means when the door has reached its fully open or closed positions, and a dashpot associated with said braking means for auto-

matically releasing the braking force thereof.

11. In combination, a door, a screw journaled adjacent said door, a motor for rotating said screw, switch means controlling the direction of rotation of said motor and screw, a cross-head carried by said screw, means connecting said cross-head and said door, and braking means adapted to be applied to the motor shaft at the opened and closed positions of the door to stop the motor, said braking means including a dashpot adapted to automatically release the braking pressure after the motor has been stopped. 70

12. The combination with a door, of power driven means for opening and closing the door, and brake means adapted to be applied to said power driven means as the door is moved into its opened and closed positions, said brake means including a dash-pot adapted to release the braking pressure after said power driven means has been stopped. 80

13. In combination, a vertically hinged door, means mounted adjacent the top of the door for applying a moving force to the door, and means connected to said first-named means and to the door adjacent the top thereof and extending down a face of the door to a point remote from the top of the door to transmit said moving force to said door normally at said remote point only, and thereafter to apply said force to the top of the door if it does not open under the force initially applied. 90

14. In combination, a vertically hinged door, a screw journaled adjacent the top of said door, a motor for rotating said screw, switch means controlling the direction of rotation of said motor and screw, a cross-head carried by said screw, means connecting said cross-head and said door for applying the moving force to the door normally locally at a point remote from the top thereof, said means extending to the top of the door and down a face of the door to said point and adapted to apply said force to the top of the door upon its failure to open under the force applied to the bottom thereof, and means for stopping said motor in the open and closed positions of the door. 100

15. In combination, a vertically hinged door, a screw journaled adjacent the top of said door, a motor for rotating said screw, switch means controlling the direction of rotation of said motor and screw, a cross-head carried by said screw, means connecting said cross-head and said door for applying the moving force to the door at a point remote from the top thereof, said means extending to the top of the door and down a face of the door to said point and including a lost-motion connection with the top of the door, and braking means adapted to be applied to the motor shaft at the opened and closed positions of the door to stop the motor. 115
